CLAIM

The ornamental design for a hydroponic basket, as shown and described.

DESCRIPTION

FIG. 1 is a perspective view of the hydroponic basket; FIG. 2 is a side elevation view of the hydroponic basket; the other three sides are identical; FIG. 3 is a top elevation view of the hydroponic basket; and, FIG. 4 is a bottom elevation view of the hydroponic basket. The broken lines in the figures depict environmental subject matter only, and form no part of the claimed design.
